J. STOREY

ASH SIFTER

Filed March 8, 1923

Inventor
Jacob Storey

By Collier Polachek Attorney.

UNITED STATES PATENT OFFICE.

JACOB STOREY, OF BERLIN, NEW HAMPSHIRE.

ASH SIFTER.

Application filed March 8, 1923. Serial No. 623,753.

To all whom it may concern:

Be it known that I, JACOB STOREY, a citizen of Russia, residing at Berlin, in the county of Coos and State of New Hampshire, have invented certain new and useful Improvements in Ash Sifters, of which the following is a specification.

This invention relates generally to sifters, being intended more particularly for embodiment in ash sifters, although not of necessity limited thereto.

The invention has for an object the provision of a novel and simple form of sifter which is efficient in operation, a further object relating to the provision of means for varying the movement given the sifting element.

For further comprehension of the invention and of the objects and advantages thereof, reference will be had to the following description and accompanying drawings, and to the appended claims in which the various novel features of the invention are more particularly set forth.

Fig. 1 of the drawings is a plan view of my improved sifter, the hinged cover being thrown back.

Fig. 2 is a longitudinal vertical sectional view taken generally along the line 2—2 of Fig. 1, but with certain additional inner parts shown partially in section.

Fig. 3 is a transverse sectional view of the sifter, taken along the line 3—3 of Fig. 2.

Fig. 4 is an end view.

As here embodied my improved sifter comprises an elongated rectangular box or casing 10 which rests upon the ground or floor and which is closed on all sides except for entrance and discharge openings for the ashes. The top of the casing is formed by a cover 10^a hinged at one end as at 10^b and having adjacent the opposite end thereof an entrance opening with which a hopper 12 registers. Extending transversely of the box just below this opening is a roller 13 which is suitably journaled at its ends in the side walls of the casing and which is provided with a number of projecting pins 14 whose function is to ensure of a continuous discharge of the material in the hopper onto the screening or sifting element.

The screening element is in the form of a box-like structure 16 of lesser dimension in all directions than the casing 10, and whose top and bottom are open, this screening element being suspended for reciprocating movement in the casing as will be presently pointed out. Extending across this structure, near the top thereof is a screen 18 which is inclined downwardly from one end, 60 which is in registry with the hopper 12, toward the opposite end. At this latter end the screen stops short of the end wall of the structure 16, leaving an opening 19 through which the ashes that have not passed 65 through the screen fall.

Extending the full area of the bottom of the structure is a second screen 20 which is inclined oppositely to the screen 18, and which effects a second screening operation 70 of the material falling from the end of the screen 18. The end wall of the structure 16 adjacent the lower end of the screen 20 is formed with a discharge opening 21 for the material which fails to pass through this 75 screen, a short spout 22 projecting from the member 16 at the bottom of this opening over a second spout 23 carried by the end wall of the casing 10 and leading through an opening 24 therein. As here shown this 80 end wall is provided with a hinged door 25 for access to the interior of the casing and the opening 21 is shown as formed in the bottom of this door.

The material passing through the top 85 screen 18 falls on a transversely inclined partition 28 located between the upper and lower screens in the member 16 and communicating at its lower side with an opening 29 in the side of the said member, the ashes 90 passing through this opening 29 and falling into the bottom of the casing from which it may be removed through any suitable door.

The screen element is suspended in the 95 casing as follows: Projecting from the sides thereof adjacent the opposite ends and near the bottom, are lugs 32 to which are fixed the lower ends of straps 33 whose upper ends are fixed to transverse bars 34 100 having pins 35 on their ends engaging in vertical guides 36 formed in longitudinal frame pieces 10'. To reciprocate the screening element I attach to the end thereof removed from the hopper 12 a forked connecting rod 37 which connects to a crank shaft 40 extending transversely of the casing 10 and suitably journaled at its ends in the walls thereof. Upon one end of this shaft 40, outside the casing, is fixed a pulley 41 110 over which is looped a belt 42 looped also over a pulley 43 on one of the trunnions of

the roller 13, the other trunnion of the roller having a crank handle 44 thereon for manual rotation, although it will be understood that other means for rotating the shaft 40 and roller 13 may be provided.

I also preferably provide in connection with my improved sifter a means for giving an upward shaking action to the screening element. As here shown a bracket 50 projects from one end of the casing 10 toward the member 16 and has pivotally mounted thereon a normally inclined finger 51 having a notch 52 formed in its free end adapted to receive the lower edge of said member as the latter nears the forward limit of its movement and cause said member to be lifted. The finger 51 is normally held in position to engage the member 16 by a tension spring 53 connected thereto and holding it against a pin 54 on the bracket 50. The finger 51 is preferably adjustable along the bracket 50 to vary the degree of movement it imparts to the screening element, and to this end it is pivoted as at 55 on a block 56 slidable in a guide groove 57 in said bracket and having threaded into one end thereof a screw 58, swiveled in the said bracket, this screw having a head 59 projecting from the casing 10 whereby it may be rotated to move the block 56. Threaded upwardly through the free end of the finger is a screw 51' which is adapted to be adjusted upwardly and downwardly as the block is moved longitudinally. As will be apparent, when member 16 engages in the notched end of the finger 51 it tends to swing the finger on its pivot 55, the end of the finger moving in an obliquely upward direction and causing the end of the screen 40 to be lifted, the pins 35 at this end of the screen moving upward in the guides 36. When the block 56 is adjusted along the groove 57 the angle of inclination of the finger, as it rests on the pin 54, is varied and in consequence the amount of upward movement imparted to the screen is varied, while by adjusting the screw 51' the latter is positioned to engage and lift the screen as soon as the vertical element of the finger end is engaged by the member 16.

While I have illustrated and described a preferred embodiment of my invention it will be understood that I do not limit myself

to the precise construction herein disclosed, and that various changes and modifications might be made therein without departing from the spirit and scope of the invention as defined in the appended claims.

Having thus described my invention what I claim as new and desire to protect by Letters Patent of the United States is as follows:

1. A sifter comprising a casing, a screening element suspended therein, said screening element consisting of upper and lower screens inclining in opposite directions, and means for reciprocating said screening element, and a transversely inclined discharge partition interposed between the upper and lower screens, said screening element including a box-like structure having discharge openings respectively in one side and end thereof, for the purpose specified. 65
2. A sifter comprising a casing, a screening element suspended in said casing, means for reciprocating said screening element, and means for giving said screening element a movement transversely to its reciprocatory motion, said means comprising a normally inclined pivoted finger adapted to be engaged by said screening element. 70
3. A sifter comprising a casing, a screening element suspended in said casing, means for reciprocating said screening element, and means for giving said screening element a movement transversely to its reciprocatory motion, said means comprising a normally inclined pivoted finger adapted to be engaged by said screening element, said finger being adjustable toward and away from said screening element, for the purpose specified. 80
4. A sifter comprising a casing, a screening element suspended in said casing, means for reciprocating said screening element, and means for giving said screening element a movement transversely to its reciprocatory motion, said means comprising a normally inclined pivoted finger adapted to be engaged by said screening element, and pin and spring means for holding said finger in position to be engaged by said screening element. 90

In testimony whereof I have affixed my signature.

JACOB STOREY.
